M. L. COSSITT,
MANIFOLDING ATTACHMENT FOR TYPEWRITERS.
APPLICATION FILED JUNE 13, 1921.

1,407,932.

Patented Feb. 28, 1922.

UNITED STATES PATENT OFFICE.

MALCOLM L. COSSITT, OF ALAMEDA, CALIFORNIA, ASSIGNOR TO MANIFOLD IMPRESSIONS CORPORATION, OF CARSON CITY, NEVADA, A CORPORATION OF NEVADA.

MANIFOLDING ATTACHMENT FOR TYPEWRITERS.

1,407,932.

Specification of Letters Patent. Patented Feb. 28, 1922.

Application filed June 13, 1921. Serial No. 477,062.

To all whom it may concern:

Be it known that I, MALCOLM L. COSSITT, a citizen of the United States, residing at Alameda, in the county of Alameda and State of California, have invented certain new and useful Improvements in Manifolding Attachments for Typewriters, of which the following is a specification.

My invention relates to that class of attachments for typewriters and other typing machines, such, for example, as calculating machines and the like, in which a manifolding ribbon is so associated with the machine as to be readily moved into and out of functional position.

The object of my invention is to provide a manifolding attachment of this class, simple in construction, effective in operation, and which can be readily and compactly applied to the machine without appreciable changes or alterations therein.

To this end my invention consists in the novel manifolding attachment which I shall now fully describe by reference to the accompanying drawings, in which—

Fig. 1 is a top plan view, broken, of my attachment, showing it applied to the platen-carriage of a machine, all the manifolding-ribbons being shown in functional position. Fig. 2 is a sectional or end view on the line 2—2 of Fig. 1, looking in the direction of the arrows; the dotted lines showing the thrown-back position of the attachment.

Fig. 3 is a section on the line 3—3 of Fig. 1, looking in the direction of the arrows.

Fig. 4 is a section on the line 4—4 of Fig. 3.

Fig. 5 is a detail showing the detachable clip-connection of the manifolding ribbon 40 with the carrying slide.

For the sake of a clear understanding, I shall first describe my attachment and then describe its application to a machine and its operation in connection therewith.

1 is a standard having a foot 1'. There are two of these standards; and they are connected by a rod 2.

3 is an arcuate housing member. There are two of these, one being pivotally mounted or journaled at its rear portion upon the rod 2 near one end thereof as shown at 2',

the other being correspondingly journaled on the rod near its other end.

Within each housing member is slidably fitted a correspondingly arcuate ribbon-carrying slide 4. In practice, there will be a plurality of these slides. I have here shown four. They lie directly one above and upon the other, as seen in Fig. 4, and have overlapping angular portions the tops of which are formed with rack teeth 8—Figs. 1 and 4. A handle 5 is formed with or fitted to each slide, and projects from the housing, so that it may be conveniently grasped, in order to move the slide.

The forward end of each slide has an extremity 4'—Figs. 2 and 3, adapted to detachably receive a clip 6 fitted to the end of a strip, section, or length of manifolding ribbon 7. The other end of each ribbon is similarly detachably connected with the extremity of the corresponding slide in the other housing member, so that the ribbons extend in parallel relation, as seen in Fig. 1, the full length between the housed slides at each end of the device, and are adapted for independent even and uniform movement, in an arcuate path.

To secure this uniform movement, each slide 4 has the rack 8, as above stated.

9 is a tubular casing fixed in bracket members 9' secured to or formed with the rear portions of the arcuate housing members 3. Within this casing 9 is carried a series of concentrically nested, independently rotatable shafts 10, each carrying at each end a pinion 11, with which the racks 8 of the corresponding ribbon connected pair of slides 4 engage. See Figs. 1 and 4.

The application of my attachment to a typing-machine will now be described.

In Figs. 1 and 2—12 indicates a part of the frame of the platen-carriage; 13 is the platen; 14 the platen shaft; 15 the platen-shaft bearings, and 16 the thumb wheel for turning the platen. 17, in Fig. 1, is the usual main inking ribbon of the machine and 18 is the index pointer. 19 is the paper guide-apron back of the platen.

The usual top members of the platen-shaft bearings 15 are removed by taking out the screws, and in place of these top members

the feet 1' of the standards 1 of my attachment are substituted and are secured by the screws 15'. The rod 2 connecting the standards, lies parallel with and above and back of the platen. The housing members 3 when thrown down, follow substantially the arc of the platen.

It will now be seen that by the movement of the slides 4 within said housings, the 10 manifolding ribbons 7 may be carried from an upper position, in which they lie in non-functional position along and above the upper part of the platen, down to their functional position in the line of type-impact, 15 and back again.

As their path of movement is substantially or approximately concentric with the curvature of the platen, due to the arcuate housings in which their carrying slides are 20 mounted, the whole attachment may be applied in close relation to the platen, thereby securing compactness, even in the non-functional position of the ribbons, and also conducing to simplicity of construction, in that 25 more or less complex provision need not be made for an eccentric or distorted path to secure the proper or accurate position of the manifolding ribbon with relation to the main ribbons and the index pointer, when 30 said manifolding ribbons reach their functional location in the line of type impact.

When, however, it is necessary to change the ribbons, their detachable clips can be conveniently reached by throwing up the 35 housing members about their pivotal connections on the rod 2, thereby elevating the ribbons a distance above the platen, as shown by the dotted lines in Fig. 2.

It will be specially noted by reference to 40 Fig. 1 that the housing members 3 extend from the rod 2 at an angle departing slightly from a right angle, so that the two members are relatively divergent. This is for the purpose of providing for the automatic tensioning of the manifolding ribbons when in 45 functional position. As the ribbon-slides 4 move down in their divergent housing members in which they are guided they are themselves caused to move in divergent paths 50 with respect to those at opposite ends, so that while not under particular tension in their upper or non-functional positions, the ribbons, upon reaching their lower or functional positions in the line of type impact 55 are placed and held under proper tension.

The operation of the attachment may now be briefly described. Ordinarily, when no 60 duplicate copy is required, all the manifolding ribbons lie above and close to the platen and are out of the way. If one duplicate is to be made, one of the handles 5 is grasped and pulled down, thereby carrying one of the ribbons down with a uniform movement at each end, said ribbon following an arcuate 65 path in front of the platen and passing be-

tween the paper sheets in the machine, until it reaches its proper position in the line of type impact. If more copies are to be made, more ribbons are pulled down. Conversely, any one or more ribbons may be raised again. 70

I claim:—

1. A manifolding attachment for typewriters and the like, comprising a pair of arcuate housing members; means for securing said members to the platen carriage of 75 the machine at each end of the platen; an arcuate slide fitted within and guided by each housing member; means connecting said slides for effecting their movement in unison; and a manifolding ribbon carried 80 by and between said slides and adapted by their movement to travel in an arcuate path about the platen from and to a functional position in the line of type-impact.

2. A manifolding attachment for typewriters and the like, comprising a pair of arcuate housing members; means for securing said members to the platen carriage of the machine at each end of the platen; an arcuate slide fitted within and guided by 90 each housing member; means connecting said slides for effecting their movement in unison; a manifolding ribbon carried by and between said slides, adapted by their movement to travel in an arcuate path about the 95 platen from and to a functional position in the line of type-impact; and means for automatically tensioning said ribbon during its travel to said position.

3. A manifolding attachment for typewriters and the like, comprising a pair of arcuate housing members; means for securing said members to the platen carriage of the machine at each end of the platen; an arcuate slide fitted within and guided by 105 each housing member; means connecting said slides for effecting their movement in unison; a manifolding ribbon carried by and between said slides, adapted by their movement to travel in an arcuate path about the platen 110 from and to a functional position in the line of type-impact; and means for causing the slides to move in relatively divergent paths towards said position whereby the ribbon is automatically placed under tension when in 115 said position.

4. A manifolding attachment for typewriters and the like, comprising a pair of arcuate housing members secured to the platen carriage of the machine one at each end of the 120 platen, and extending forwardly in divergent planes with relation to each other; an arcuate slide fitted within and guided in relatively divergent forward paths by each housing member; means connecting said 125 slides for effecting their movement in unison; and a manifolding ribbon carried by and between said slides, adapted by their movement to travel in an arcuate relatively angular path about the platen from and to a 130

functional position under tension in the line of type-impact.

5. A manifolding attachment for typewriters and the like, comprising a pair of arcuate housing members; means for securing said members to the platen-carriage of the machine at each end of the platen; an arcuate slide fitted within and guided by each housing member, each of said slides 10 having a rack; a rotatable member carried by and extending between said housing members; a pinion at each end of said rotatable member, engaging the rack of the corresponding slide, whereby said slides move in unison; and a manifolding ribbon carried by and between said slides adapted by their movement to travel in an arcuate path about the platen from and to a functional position in the line of type-impact.
- 15 6. A manifolding attachment for typewriters and the like, comprising a pair of standards adapted to be mounted on the platen carriage of the machine at each end of the platen; a rod extending between said 20 standards; a pair of arcuate housing members pivotally mounted upon said rod, near each end; means connecting said housing members, whereby they may be moved in unison about their pivotal connections; an 25 arcuate slide fitted within and guided by each housing member; means for effecting 30

the movement of said arms in unison; and a manifolding ribbon carried by and between said slides, adapted by their sliding movement to travel in an arcuate path about the 35 platen from and to a functional position in the line of type-impact.

7. A manifolding attachment for typewriters and the like, comprising a pair of arcuate housing members; means for securing said members to the platen-carriage of the machine at each end of the platen; a plurality of independent parallel, arcuate slides fitted within and guided by each housing member, each of said slides having a 40 rack; a nested series of concentric independently rotatable members carried by and extending between said housing members; a pinion at each end of each of said rotatable members, engaging the rack of corresponding 45 slides whereby each pair of corresponding slides is adapted to move in unison and independently of other corresponding pairs; and a manifolding ribbon carried by and between each pair of corresponding slides 50 adapted by the movement of said pair to travel in an arcuate path about the platen from and to a functional position in the line of type impact.

In testimony whereof I have signed my 55 name to this specification.

MALCOLM L. COSSITT.
